F. H. GOODRICH

JACK

Filed June 5, 1924

UNITED STATES PATENT OFFICE.

FREDERIC HARRISON GOODRICH, OF GREENVILLE, MICHIGAN.

JACK.

Application filed June 5, 1924. Serial No. 718,102.

To all whom it may concern:

Be it known that I, FREDERIC HARRISON GOODRICH, a citizen of the United States, and a resident of Greenville, in the county of 5 Montcalm and State of Michigan, have invented certain new and useful Improvements in Jacks, of which the following is a specification.

This invention relates to jacks and is more 10 particularly directed to a jack for shifting paper rolls.

The invention has for its object the provision of a simple and inexpensive but efficient jack for lifting the heavy rolls of paper 15 from a press or for applying the rolls to a press.

A further object of the invention is the provision of a jack for lifting heavy rolls of paper having cooperating pawls operated by a single lever for raising or lowering 20 the jack by differential movements of the lever.

A still further object of the invention is the provision of a jack which is particularly 25 useful in handling paper rolls and operating in conjunction with a fulcrum block braced by an end of the press whereby the rolls are readily removed from or replaced in a press, the jack being so designed that the rolls may 30 be received directly on the jacks from a truck.

Other objects and advantages of the invention reside in certain novel features of the construction, combination and arrangement 35 of parts which will be hereinafter more fully described and particularly pointed out in the appended claims, reference being had to the accompanying drawings forming part of this specification, and in 40 which:

Figure 1 is a side view of the jack as applied for removing a roll from a press;

Figure 2 is a plan view of the jack;

Figure 3 is an enlarged fragmentary sectional view of the controlling pawls for raising and lowering the supporting rails.

Referring more particularly to the drawings, 1 and 2 designate a pair of rails secured in spaced relation by bolts 3 and spacing sleeves 4 and 5. The sleeve 4 and its corresponding bolt also act as a fulcrum pin to be presently explained. The rails are directed towards each other at their outer ends where a rack 6 is slidably received and movable between said ends. The inner ends

of the rails are curved upwardly, as shown at 7, to receive the shaft 8 of a paper roll 9.

A fulcrum block 10 having a slot 11 to receive the sleeve 4 at the inner ends of the rails is adapted to abut the outer end of a 60 press 12. The outer end of the block is cut away to provide a securing flange 13 which is bolted at 14 to the floor of the press room.

The rack 6 is provided with a longitudinal slot 15 which receives a guide block 16 on 65 rail 1.

At one side of the rack 6 and between said rack and rail 2 is pivotally mounted the horizontal portion 17 of a lever 18 on a pin or bolt 19 fastened to the rails. The inner end 70 of the horizontal portion of said lever has an angularly disposed lug 20 provided with an engaging shoulder 21. This shoulder engages the rear edge of rack 6 and limits the upward movement of said lever. From the 75 horizontal portion 17 the lever 18 is bent upwardly and adapted to be grasped by the hand for operating said lever.

A pawl 22 is pivoted at 23 to the horizontal portion 17 of said lever and is adapted 80 to engage the teeth of the rack 6 at certain times. A spring 24 mounted on a pin 25 secured to the rail 2 engages a pin 26 on the pawl and tends to force the pawl out of engagement with the teeth of the rack. 85 The pawl 22 has a rearwardly projecting lug 27 provided with a notch 28 engageable with the upper free end 29 of a downwardly curved spring 30 of flat steel and which is secured to the inner face of a large pawl 31. 90

The lower end of the spring 30 is curved inwardly as shown at 32 and is disposed below the pawl 22. A pin 33 is secured to rail 1 and is adjacent a notch 34 in pawl 31 and limits the outward movement of said 95 pawl. A pin 35 is secured to pawl 31 and provides a means for releasing the pawl 31 as will be presently explained.

A pair of wheels 36 are mounted on axle 37 carried by the lower end of the rack for 100 supporting said rack during operation of the jack and so provides an easy means of transportation of said jack in the press room. An enlargement of the axle or a sleeve 38 is provided to maintain the wheels 105 in position.

A rest or roll shaft support 39 projects upwardly from between the rails 1 and 2 and is formed on the end of a bar 40 pivoted at 41 to rail 1. A pin 42 on rail 1 limits 110

the downward movement of the inner end of bar 40 and prevents upward or rearward movement of the rest 39. A spring 43 secured at one end to rail 1 has its other end attached to the outer end of the bar 40 and maintains the inner end of said bar in engagement with pin 42. A pin 45 connected to the rails engages the spring 30 at times during movement of the lever 18 for causing said spring to force pawl 31 into engagement with the teeth of rack 6.

10 The paper roll shifting jack is primarily designed to be used in connection with a Duplex, Goss Comet and similar web presses using one or two rolls of paper.

15 The paper roll, after being placed on the usual paper roll shaft supplied with a press, is placed between two jacks constructed according to my invention with the opposite 20 ends of the shaft resting on the rails near the jack or outer end engaging the rest 39 to prevent the roll from sliding down the rails before the rolls are released from the truck. The levers 18 are then raised to 25 their full height by two workmen and then forced downwardly through half of their stroke whereby the rails are elevated. This operation is repeated until the roll is free of 30 the truck body. The truck is then shifted 35 from the jacks and the levers 18 are then lowered and elevated through the lower portion of their strokes when the rails will descend. This operation is continued until the rail approaches a substantially horizontal 40 position when rest 39 is depressed and the roll is revolved until it reaches the curved portions 7 of the rails and falls into the socket of the press 12 beyond the fulcrum block 10.

45 In removing the rolls from the press, the jack is placed in position with the curved portions 7 of the rails in engagement with the roll shaft 8 and the fulcrum sleeves 4 in the grooves of the fulcrum blocks 10. The outer ends of the rails are lowered by operating the levers 18 through the lower half of their stroke. The curved ends of the rails are thus elevated, lifting the rolls from the press.

50 When the lever 18 is raised to its full height and limited by the lug 20 and rack 6, pawl 22 is oscillated by the curved end 29 of spring 30 coming into contact with the notch of lug 27 carried by said pawl so that 55 the pawl is engaged with the teeth of the rack. Downward movement of the lever through its upper half stroke tilts the inner end of the lever upwardly raising the jack end of the rails since said lever is fulcrumed 60 on the rack by pawl 22. Pawl 31 swings away from the rack when the lever is lowered but is moved into engagement with a tooth in the rack by spring 30 and supports the rails during transposition of the pawl 65 22. Continued oscillation of lever 18 in its

upper half stroke elevates the jack end of the rails.

When lever 18 is actuated through the lower half of its stroke the lug 27 of pawl 22 is not engaged by spring 30 whereby the spring 24 will force the pawl 22 out of engagement with the teeth of the rack 6 and pawl 31 will fall into a notch in the rack and hold the rails during transposition of the pawl 22. The lower end 32 of spring 30 will move pawl 22 into engagement with the rack when pawl 31 has been set. When pawl 22 acts as a fulcrum for slightly raising the rail pawl 31 will fall out of a notch on rack 6 and engage a notch lower on the rack as 80 the rails are lowered.

By exerting a pull on pin 35, pawl 31 is released and the rails may be moved downwardly or upwardly. Spring 24 releases pawl 22 during manual operation of pawl 31. 85

I claim:

1. A lifting jack comprising a rack, a pair of rails slidably receiving at one end the rack, a lever pivoted to the jack end of the rails, a pawl pivoted on the lever and engaging the teeth of said rack, a pawl pivoted on the rail adjacent the rack and engageable with the teeth of the rack, a spring carried by the second pawl for causing the first pawl to engage the rack and at another 95 time for causing the second pawl to engage said rack. 90

2. A lifting jack comprising a rack, a pair of rails slidably receiving at one end the rack, a lever pivoted to the jack end of the rails, a pawl pivoted on the lever and engaging the teeth of said rack, a pawl pivoted on the rail adjacent the rack and engageable with the teeth of the rack, a spring carried by the second pawl for causing the first pawl to engage the rack and at another time for causing the second pawl to engage said rack, and means in the path of said spring engaging the spring for causing the spring to force the second pawl only in engagement with the rack. 100

3. A lifting jack comprising a rack, a pair of rails slidably receiving at one end the rack, a lever pivoted to the jack end of the rails, a pawl pivoted on the lever and engaging the teeth of said rack, a pawl pivoted on the rail adjacent the rack and engageable with the teeth of the rack, a spring carried by the second pawl for causing the first pawl to engage the rack and at another time for causing the second pawl to engage said rack, means in the path of said spring engaging the spring for causing the spring to force the second pawl only in engagement with the rack, and means for forcing the second pawl out of engagement with the rack during the forced engagement of the second pawl with said rack. 115

4. A lifting jack comprising a rack, a pair of rails slidably receiving at one end the 120

rack, a lever pivoted to the jack end of the rails, a pawl pivoted on the lever and engaging the teeth of said rack, a pawl pivoted on the rail adjacent the rack and engageable with the teeth of the rack, a spring carried by the second pawl for causing the first pawl to engage the rack and at another time for causing the second pawl to engage said rack, and means on the first pawl engaged by the spring whereby said pawl is moved to an operative position with the rack.

5. A lifting jack comprising a rack, a pair of rails slidably receiving at one end the rack, a lever pivoted to the jack end of the rails, a pawl pivoted on the lever and engaging the teeth of said rack, a pawl pivoted on the rail adjacent the rack and engageable with the teeth of the rack, a spring carried by the second pawl for causing the first pawl to engage the rack and at another time for causing the second pawl to engage said rack, said spring having a curved upper and lower portion adapted to engage the first pawl during various movements of the lever for actuating said pawl to an operative position with the rack.

6. A lifting jack comprising a rack, a pair of rails slidably receiving at one end the rack, a lever pivoted to the jack end of the rails, a pawl pivoted on the lever and engaging the teeth of said rack, a pawl pivoted on the rail adjacent the rack and engageable with the teeth of the rack, a spring carried by the second pawl for causing the first pawl to engage the rack and at another time for causing the second pawl to engage said rack, a movable support carried by the rails near the jack end for maintaining a proper roll in position adjacent the rack.

7. A lifting jack comprising a rack, a pair of rails slidably receiving at one end the rack, a lever pivoted to the jack end of the rails, a pawl pivoted on the lever and en-

gaging the teeth of said rack, a pawl pivoted on the rail adjacent the rack and engageable with the teeth of the rack, a spring carried by the second pawl for causing the first pawl to engage the rack and at another time for causing the second pawl to engage said rack, a movable support carried by the rails near the jack end for maintaining a proper roll in position adjacent the rack, said support being spring pressed to operative position and adapted to be depressed for releasing said roll.

8. A lifting jack comprising a rack, a pair of rails slidably receiving at one end the rack, a lever pivoted to the jack end of the rails, a pawl pivoted on the lever and engaging the teeth of said rack, a pawl pivoted on the rail adjacent the rack and engageable with the teeth of the rack, a spring carried by the second pawl for causing the first pawl to engage the rack and at another time for causing the second pawl to engage said rack, manual means connected with the second pawl for releasing the same whereby the rails may be elevated or lowered near the jack end independently of the operating pawls and lever.

9. A lifting jack comprising a rack, a pair of rails slidably receiving at one end the rack, a lever pivoted to the jack end of the rails, a pawl pivoted on the lever and engaging the teeth of said rack, a pawl pivoted on the rail adjacent the rack and engageable with the teeth of the rack, a spring carried by the second pawl for causing the first pawl to engage the rack and at another time for causing the second pawl to engage said rack, manual means connected with the second pawl for releasing the same whereby the rails may be elevated or lowered near the jack end independently of the operating pawls and lever, and means for limiting the upward throw of the lever.

FREDERIC HARRISON GOODRICH.
